(Cl. D2—3)

To all whom it may concern:

Be it known that we, Howard F. Addleston and Gertrude I. Smith, citizens of the United States, residing at 3050 23rd Avenue, San Francisco, California, and 220 16th Avenue, San Francisco, California, respectively, have invented a new, original, and ornamental Design for a Liquid Dispensing Device, of which the following is a specification, reference being had to the accompanying drawing, forming part thereof.

Fig. 1 is a perspective view of a liquid dispensing device, showing our new design.

Fig. 2 is a front end elevational view of the liquid dispensing device shown in Fig. 1.

Fig. 3 is a rear end elevational view of the liquid dispensing device shown in Fig. 1.

We claim:

The ornamental design for a liquid dispensing device, as shown.

HOWARD F. ADDLESTON.
GERTRUDE I. SMITH.
